UNITED STATES PATENT OFFICE.

JOHN OLSON, OF BELGRADE, MINNESOTA.

WIRE-FENCE STRETCHER.

1,157,324.

Specification of Letters Patent. Patented Oct. 19, 1915.

Application filed December 9, 1914. Serial No. 876,317.

To all whom it may concern:

Be it known that I, JOHN OLSON, a citizen of the United States, residing at Belgrade, in the county of Stearns and State of Minnesota, have invented certain new and useful Improvements in Wire-Fence Stretchers, of which the following is a specification, reference being had to the accompanying drawings.

- 10 This invention relates to improvements in wire fence stretchers and has for its primary object to provide a simple and effective device for easily and quickly stretching or tightening wire fence fabric.
- 15 The invention has for one of its more specific objects to provide a stretching device embodying drums carried by the fabric clamp, flexible members to be wound upon said drums adapted to be connected to one 20 of the fence posts, a ratchet on each drum, and a pawl to engage said ratchet, novel means being provided for mounting said pawl in position and shifting the same into or out of coöperating engagement with the 25 ratchet.

The present invention also aims to generally improve devices of the above character whereby the same are rendered extremely strong and durable and capable of operation with a minimum of manual labor.

With the above and other objects in view, my invention consists in the novel features of construction, combination, and arrangement of parts to be hereinafter more fully 35 described, claimed, and illustrated in the accompanying drawing, in which,

Figure 1 is an elevation of a wire fence stretcher constructed in accordance with the preferred embodiment of my invention; Fig. 40 2 is a section taken on the line 2—2 of Fig. 1, showing the pawl in an inoperative position in dotted lines; and Fig. 3 is a detail perspective view of the bracket member in which the drum is mounted.

45 Referring in detail to the drawing, 5 designates the clamping bar which consists of two sections adapted to be arranged upon opposite sides of the wire fence fabric 6 and securely clamped upon the same by 50 means of a plurality of removable bolts 7. It will be understood, that in the application and use of my invention any other approved type of clamp may be employed, instead of the conventional form illustrated.

55 To the edge of the main body section of the clamp 5 adjacent the upper and lower

ends thereof, bearing brackets 8 are secured. Each of these brackets consists of a body plate having openings to receive the securing bolts 9 which extend through the body 60 bar of the clamp, and laterally extending arms 10 formed upon said body plate at its opposite ends. This plate is also provided with an integral longitudinal extension 11 on one of its ends secured to the clamping 65 bar by a suitable screw or other fastening means. The particular purpose of this extension of the bearing will be later pointed out.

The outer ends of the arms 10 of each 70 bearing bracket are provided with openings in which a vertically disposed bolt 12 is loosely mounted. This bolt serves as a drum upon which a cable or chain 13 is adapted to be wound, said bolt having an opening 75 therein or other means for conveniently attaching one end of the cable to the same. The upper end of this bolt is provided with a rectangular head 14 and upon the lower end thereof, a ratchet member 15 is securely 80 fixed by means of the pin 16 extending transversely through said ratchet member and the bolt 12.

In the edge of the body bar of the clamp 5, a circular socket or recess 17 is formed 85 with which an opening 18 in the extension 11 of the bearing bracket is adapted to register or coincide. 19 designates a pawl 90 loosely disposed through the opening 18 and provided with an enlarged head 20 loosely 95 fitting within the recess 17 of the clamping bar. It will thus be seen that the extension 11, in addition to providing an auxiliary fastening means for the bearing bracket, also serves to retain the pawl in place. The 100 recess 17 in the clamping bar is of sufficient diameter to permit of a vertical movement of the pawl member so that its outer end may be disengaged from the teeth of the ratchet 15. The pawl 19 is in the form of a cylindrical pin having a pointed or tapering outer end 21 for engagement with the teeth of the ratchet.

In the use of my invention, the clamp is first secured to the end of the wire fabric, 105 and the cables 13 connected to the respective drums are suitably attached at their free ends to the fence post indicated at P. The operator now applies a suitable wrench to the rectangular head 14 of the winding 110 drum and rotates the same in the proper direction to wind the cable thereon. It will

be understood that the drum is held against reverse turning movement by means of the pawl 19. The two cables are alternately wound upon the respective drums in this manner so that the wire fence fabric is pulled taut or tightened. After the fabric has been suitably secured to the fence post, the cables may be readily unwound from the drums by simply knocking the pawls 19 upwardly so as to disengage their tapered or pointed ends from the ratchets 15. In this manner, it will be seen that the fence fabric may be very easily and quickly stretched or tightened.

15 From the foregoing description, it will be seen that I have produced a simply constructed, strong and durable stretcher for wire fencing which may be easily and quickly applied to or removed from the fence fabric and requires comparatively little manual labor in its operation. By mounting the pawl member 19 in the manner above explained, the bearing bracket in which the drum is mounted to rotate, is relieved of the excessive strain which would otherwise take place, if the pawl was mounted directly upon one of the bracket arms. By disposing the inner end of the pawl in bearing contact with the clamping bar, the pressure is applied directly to the bar and liability of displacement of the pawl reduced to a minimum.

20 25 30 While I have above set forth the preferred construction and arrangement of the

several elements employed, it is to be understood that the invention is susceptible of considerable modification and I, therefore, reserve the privilege of resorting to all such legitimate changes as may be fairly embodied within the spirit and scope of the 35 40 invention as claimed.

Having thus fully described my invention, what I desire to claim and secure by Letters Patent is:—

The combination with a clamping bar, of 45 a bearing bracket provided with an integral extension having an opening therein, means for securing said bracket to the clamping bar, a drum rotatably mounted in the bearing bracket, a stretching cable connected to 50 said drum, said clamping bar having a circular recess therein of greater diameter than the opening in the bearing extension, a ratchet member fixed upon one end of the drum, and a rigid pawl loosely disposed 55 through the opening in the bearing extension and having an enlarged head on one end loosely fitting in the recess in the clamping bar, the other end of said pawl being tapered for engagement with the teeth of the 60 ratchet member.

In testimony whereof I hereunto affix my signature in the presence of two witnesses.

JOHN OLSON.
